UNITED STATES PATENT OFFICE.

BENJAMIN SCARLES, OF CLINTON, MASSACHUSETTS, ASSIGNOR TO THE
CLINTON WIRE CLOTH COMPANY, OF SAME PLACE.

METALLIC LATHING.

SPECIFICATION forming part of Letters Patent No. 388,920, dated September 4, 1888.

Application filed July 18, 1887. Serial No. 244,578. (No model.)

To all whom it may concern:

Be it known that I, BENJAMIN SCARLES, of Clinton, in the county of Worcester, State of Massachusetts, have invented a certain new and useful Improvement in Metallic Lathing, of which the following is a description sufficiently full, clear, and exact to enable any person skilled in the art or science to which said invention appertains to make and use the same, reference being had to the accompanying drawings, forming part of this specification, in which—

Figure 1 is a plan view of a piece of my improved lathing, represented as in position for use; Fig. 2, a side elevation showing the method of attaching the furring to the beam; Fig. 3, a side elevation of a piece of the furring detached, and Figs. 4 and 5 side elevations showing modified forms of the furring.

Like letters of reference indicate corresponding parts in the drawings.

My invention relates to that class of metallic lathing in which the body for receiving and holding the imposed plastering is composed of wire-cloth; and it consists in a novel construction and arrangement of parts, as hereinafter more fully set forth and claimed, the object being to produce a simpler, cheaper, and more desirable article of this character than is now in ordinary use.

The nature of the improvement will be readily understood by all conversant with such matters from the following explanation.

In the drawings, A represents the wire-cloth or body of the lathing; B, the furring, and C the beam or other wood-work to which the lathing is attached.

The wire-cloth may be of any suitable gage or mesh.

The furring-strips are composed of pieces of wire m^x , the ends of each piece being bent at right angles to its body and the pieces connected by twisting their ends together adjacent to their bodies, as shown at t, the number of coils in the twists being varied in accordance with the distance it is desired to have the furring-strip stand from the beam or wood-work to which it is secured.

The free ends of the pieces m^x are preferably

chamfered or beveled on their inner edges, as shown at b in Fig. 3, so that when driven into the beam or wood-work they will spread and "clinch," as shown by the dotted lines in Fig. 2, thereby firmly securing the lathing. The ends may, however, be flattened, as shown in Fig. 4, or pointed, as shown in Fig. 5, or left unpointed, as desired, provided they are adapted to be driven into the wood-work.

It will of course be understood that the length of the pieces m^x may be varied, as desired, and that the number employed will be governed by the length of the furring strip.

In attaching the wire-cloth body of the lathing to the furring I preferably employ staples v, which are so arranged as to embrace both a warp and filling wire of the cloth and also the furring, the staples being placed near the twists t and driven into the beam or wood-work, as shown in Fig. 1. The staples may, however, be disposed in any other suitable position, or any other suitable means employed for securing the cloth to the furring, if desired.

It will be obvious that a furring constructed as described is exceedingly simple, cheap, and durable, and is well adapted for use on irregular and curved surfaces, where it is difficult to use many kinds of the ordinary metallic furring.

I do not confine myself to forming the bevels b on the adjacent edges of the ends f, as they may be placed in other positions and perform substantially the same functions.

Having thus explained my invention, what I claim is—

1. As an improved article of manufacture, a furring-strip composed of pieces of wire, the adjacent ends of which pieces are bent at an angle to their bodies and connected by being twisted together, said ends being adapted to be driven into a beam or wood-work in attaching the furring thereto, substantially as described.

2. In a furring-strip, the pieces m^x , having their adjacent ends twisted together, as shown at t, and beveled to deflect and clinch them when driven into the beam or wood-work, substantially as described.

3. In a metallic lathing of the character described, the combination of the furring-strip B, body A, and staples v, said strip being composed of pieces of wire, the adjacent ends of which are bent at an angle to their bodies and twisted together, and said ends being adapted to be driven into the beam C, and said staples embracing one weft and one warp

strand of said wire-cloth A, and being also adapted to be driven into the beam C over the twisted junctions of said pieces, substantially as described.

BENJAMIN SCARLES.
